(57) CLAIM

The ornamental design for a lick mat as shown and described.

DESCRIPTION

FIG. 1 is a top perspective view of a lick mat showing my new design

FIG. 2 is a top view thereof;

FIG. 3 is a bottom view thereof;

FIG. 4 is a rear view thereof;

FIG. 5 is a front view thereof;

FIG. 6 is a right side view thereof; and,

FIG. 7 is a left side view thereof.

The broken lines in the drawings depict portions of the lick mat that form no part of the claimed design.
